UNITED STATES PATENT OFFICE.

JUSTUS R. KINNEY, OF BOSTON, MASSACHUSETTS.

ROTARY PUMP.

1,079,561.

Specification of Letters Patent.

Patented Nov. 25, 1913.

Application filed October 20, 1910, Serial No. 588,210. Renewed April 16, 1913. Serial No. 761,560.

To all whom it may concern:

Be it known that I, JUSTUS R. KINNEY, a citizen of the United States of America, and a resident of Boston, county of Suffolk, and 5 State of Massachusetts, have invented certain new and useful Improvements in Rotary Pumps, of which the following is a specification.

This invention relates to rotary pumps 10 which has for its object the provision of a pump of a simple construction having comparatively few operating parts, thereby reducing its liability to become inoperative.

The invention consists primarily in providing a piston mounted upon a crank member or eccentric, and securing thereto or forming thereon a projection provided at its outer end with a semi-cylindrical portion fitting accurately a semi-cylindrical 20 groove in the pivoted blade.

The invention consists in certain novel features of construction and arrangement of parts which will be readily understood by reference to the description of the drawings and to the claims hereinafter given:

Of the drawings: Figure 1 represents a vertical section of a pump embodying the features of the present invention, and Fig. 2 represents a longitudinal vertical section 30 of the same, the cutting plane being on line 2, 2 on Fig. 1.

Similar characters designate like parts throughout the several figures of the drawings.

35 In the drawings, 10 represents a casing supported by the feet 11, and having a cylindrical piston chamber 12, and inlet and outlet compartments 13 and 14 respectively. A passage 15 forms a means of communication 40 between the inlet compartment 13 and the piston chamber 12, while a similar passage 16 forms a means of communication between the piston chamber 12 and the outlet compartment 14.

45 Extending through the piston chamber 12 is a shaft 17 revolvable in bearings 18 in the end plates 19 secured to this casing 10. This shaft 17 has secured thereto within the piston chamber 12 two eccentrics 20, 50 these two eccentrics being separated by the divisional wall 21.

The eccentrics 20 are keyed to the shaft 17 and revolve therewith. Upon each of the eccentrics 20 is mounted an annular piston 55 member 22, which is adapted to always contact at one point in its periphery with the

cylindrical wall of said piston chamber during the rotation of the shaft 17. Obviously, where two piston members 22 are used, they are oppositely disposed so that the contacting points on their peripheries are diametrically opposite each other. Each piston member 22 is provided with a dovetailed groove 23, in which is inserted the projecting member 24, provided on its outer 60 end with a semi-cylindrical portion 25, accurately fitting a transverse semi-cylindrical groove in the blade 27 pivoted at 28 to the casing 10 and the central support 29. The pivotal portion 28 of the blade 27 is 65 mounted in a semi-cylindrical bushing 30 which is made non-revolvable by the key 31 inserted partially in the groove in said bushing and partially in the central support 29. The outer curved face of the pivoted blade 70 27 is provided with the usual packing members 32 to prevent any leakage between this outer face and the co-acting face of the casing 10. Each piston member 22 extends from the end plates 19 to the divisional wall 80 21, and these piston members are provided at each end thereof with packing members 33 bearing against said end plates 19 and divisional wall 21, thus preventing any leakage by the end of the piston members during 85 their rotation.

As the shaft 17 is rotating the eccentric 20 will rotate therewith within the annular piston members 22, which annular piston members will have a slight oscillation on 90 said eccentrics 20 during such rotation. During this oscillation the semi-cylindrical end 25 has a slight oscillatory movement within the semi-cylindrical recess 26, and the pivoted member 27 is moved about the pivot 28 95 to accommodate itself to the various positions of the piston member 22 during the rotation of the shaft 17 and its eccentric 20.

By this construction the use of pivoted shoes bearing upon the piston member 22 100 and carried by the pivoted blade 27 is wholly obviated. Heretofore, in devices of this class, where these shoes are used, the continuous contact with the periphery of the rotating piston causes them to become quickly 105 worn and as a consequence leakages are liable to occur between the piston and said shoe, while oftentimes the edges of the shoes engage with the periphery of the piston and injure it. These objections are wholly overcome by means of the projection 24 secured permanently to the annular piston 110

member and pivotally connected to the pivoted blade 27. It is obvious that by this construction, wherein a permanent pivotal connection is made between the annular piston member and the pivoted blade, the rocker or other members heretofore necessary to force the pivoted blades into contact with the periphery of the rotating pistons, are wholly dispensed with, thereby reducing the parts of the pump to a minimum, and as a consequence materially reducing the liability of the pump to become inoperative.

In order to provide suitable lubrication between the annular member 22 and the eccentric 20, the annular member 22 is provided with a passage 34 on the discharge side of the projection 24, said passage extending from the periphery of said annular member to a groove 35 cut into the inner wall of said annular member. The water or other liquid being pumped will be discharged through the passage 16 under pressure, and a portion of this water or other liquid under pressure will pass through the opening 34 into the groove 35, and the pressure of this liquid interposed between the periphery of the eccentric 20 and the inner wall of the member 22 will tend to force said member outwardly in every direction, thus obtaining a very free movement of the eccentric within said annular member. The water or other liquid in the groove 35 will be forced outwardly in either direction between the eccentric and annular member and ultimately pass beyond the ends of said annular member and effect a suitable seal between the ends thereof and the end plates 19. Any water or liquid passing by the packings 33 will return into the piston chamber 12. This forms a very effectual means of lubricating the eccentric 20, whereby it is permitted to move freely within the surrounding annular member 22.

It is believed that the operation and many advantages of the invention will be thoroughly understood without any further description.

Having thus described my invention, I claim:

1. In a device of the class described, the combination of a casing provided with a

piston chamber and inlet and outlet passages communicating therewith; a revoluble piston therein; an annular member surrounding said piston and adapted to bear at one point in its periphery upon the wall of said piston chamber, said member having an annular groove in its inner cylindrical wall; means for admitting liquid under pressure to said groove; and a projection from said annular member interposed between said inlet and outlet passages and adapted to prevent the direct passage of liquid from one passage to the other.

2. In a device of the class described, the combination of a casing provided with a piston chamber and inlet and outlet passages communicating therewith; a revoluble piston therein; an annular member surrounding said piston and adapted to bear at one point in its periphery upon the wall of said piston chamber, said member having an annular groove in its inner cylindrical wall; a passage through said annular member communicating with the outlet passage adapted to admit liquid under pressure to said groove; and a projection from said annular member interposed between said inlet and outlet passages and adapted to prevent the direct passage of liquid from one passage to the other.

3. In a device of the class described, the combination of a casing provided with a piston chamber and inlet and outlet passages communicating therewith; a revoluble piston therein; and an annular member surrounding said piston and adapted to bear at one point in its periphery upon the wall of said piston chamber, said member being provided with means projecting therefrom to prevent the direct passage of liquid from one passage to the other and having an annular groove in its inner cylindrical wall communicating with said outlet passage by a single passage adjacent said projecting means.

Signed by me at Boston, Mass., this 17th day of October, 1910.

JUSTUS R. KINNEY.
